UNITED STATES PATENT OFFICE

2,619,071

PEN NIB ATTACHMENT

Julián Igual Albrich, Barcelona, Spain, assignor
of one-half to Jaime Isern Miralles, Barcelona,
Spain

Application February 25, 1948, Serial No. 10,812
In Spain December 6, 1946

Section 1, Public Law 690, August 8, 1946
Patent expires December 6, 1966

1 Claim. (Cl. 120—114)

1

The present invention relates to an improvement in pen nibs used mainly for writing showcards and known as "Showcard Nibs."

More specifically, the present invention relates to improvements in showcard nibs of the kind comprehending a container cover over the convex portion of the pen hingedly mounted on a supporting clip which is fixed in a detachable manner by its own elasticity over the body of said pen and resilient means which correlate both the members such as to determine their relative position, forming a receptacle for the ink, adapted to be opened for purpose of allowing the cleaning of the pen.

The object of the present invention is to provide a writing device of the specified kind in which the blade spring destined to maintain the container cover in its positions of working and cleaning, is constituted by a rear portion of the container cover, comprehended within two parallel incisions in part of the length thereof and reaching its rear end, without any waste of the starting material.

A further object of the present invention is to provide a supporting clip for the said container cover wherein the points of support and rotation for the same are constituted by a central portion of the rear part of the said supporting clip, bent upwardly for providing a point of support of the end of the blade spring, and two lateral ends of said central portion bent forwardly in an arrangement such as to have co-axial orifices in which the conventional lugs are to be coupled and which constitute the points of rotation of the said container cover.

The invention is illustrated by way of example in the accompanying drawing in which:

Fig. 1 shows an elevation of the device and the nib, the device being closed down onto the nib, in which position it forms a cover for the ink container, and shows in dotted lines the device in the raised position in order to facilitate cleaning.

Fig. 2 is a plan view of the device.

Fig. 3 shows a perspective view of the device shown in Fig. 1.

Fig. 4 is an expanded view in the order of sequence, that is to say, the nib, the clip of the container-cover device and finally the cover device itself, and

Fig. 5 shows, in perspective, the hinged assem-

bly of the container-cover device with its clip but without the nib.

The container-cover device comprises two parts, shown in the drawings by the reference numbers 1 and 2. Reference numeral 1 is the holding clip which serves as a seating for the container-cover device 2 and for securing it to the nib. This seating has two orifices through which pass the pivotal lugs with which the container-cover device is provided.

The container-cover device comprises a tongue having in its centre an orifice and intended solely for forming with the nib 3 the cavity in which the ink is placed. At its rearward end it incorporates two small lugs which act as pivotal guides by which it is hingedly mounted on the supporting clip, and a blade spring which is obtained by means of two parallel cuts, as shown in detail in the drawing, the said blade spring exercising the necessary pressure for securing the container-cover device 2 against the body of the nib 3, and can be raised when a slight pressure is applied in that direction, whereupon it remains in vertical position as indicated in Fig. 3 of the drawing.

When the container-cover device 2 is in the raised position, the nib is in a suitable position for cleaning without the need for removing it. Thereupon, by applying a gentle pressure the container-cover device 2 returns to its normal position forming an integral whole with the nib, capable of being used for writing and ensuring easy cleaning.

The body of the nib 3 consists of a strip of any material intended for supporting the hinged member and for forming therewith the cavity for holding the ink.

Having now particularly described and ascertained the nature of my said invention, and in what manner the same is to be performed, I declare that what I claim is:

A writing device comprising a clip and a container cover hinged thereto, an upstanding projection on the central rear portion of said supporting clip, said container cover having two parallel incisions in part of the length thereof extended to the rear end of said container cover, one portion of said container cover comprehended within said incisions and constituting a blade spring which has a rear end projecting from the rear end of said container cover bear-

ing upon the upper edge of said upstanding projection of said clip for retaining the said container cover, alternatively, in a working position and in a position substantially perpendicular with respect to the former, and two lateral portions at both sides of said parallel incisions having at the rear ends thereof conventional lugs for the pivoting of said container cover to said clip.
